(57) **CLAIM**

The ornamental design for eyeglass display stand, as shown and described.

DESCRIPTION

FIG. 1 is a perspective view of the eyeglass display stand of the present invention;

FIG. 2 is a front elevational view of the eyeglass display stand as shown in FIG. 1;

FIG. 3 is a back elevational view of the eyeglass display stand as shown in FIG. 1;

FIG. 4 is a right side elevational view of the eyeglass display stand as shown in FIG. 1, with the left side elevational view being a mirror image thereof;

FIG. 5 is a top plan view of the eyeglass display stand shown in FIG. 1; and,

FIG. 6 is a bottom plan view of the eyeglass display stand as shown in FIG. 1.

The broken lines are for environmental purposes and form no part of the claimed design.

1 Claim, 6 Drawing Sheets
